(57) **CLAIM**

(21) Appl. No.: **29/307,482**

The ornamental design for a rotation rate detector, as shown.

(22) Filed: **Apr. 23, 2008**

(30) **Foreign Application Priority Data**

Oct. 30, 2007 (JP) 2007-029894

DESCRIPTION

(51) **LOC (9) Cl.** **10-04**

FIG. 1 is a perspective view of a rotation rate detector showing my new design;

(52) **U.S. Cl.** **D10/98**

FIG. 2 is a front view thereof;

(58) **Field of Classification Search** D10/98;

FIG. 3 is a rear view thereof;

73/862,331–862,336; 307/116; 310/71,
310/179, 258–260; 324/207.25, 207.15,
324/207.16, 207.17, 173, 174, 207.11, 207.13;
338/32 H, 32 R; 361/380, 395, 399

FIG. 4 is a top plan view thereof;

See application file for complete search history.

FIG. 5 is a bottom plan view thereof;

(56) **References Cited**

FIG. 6 is a right side view thereof; and,

U.S. PATENT DOCUMENTS

FIG. 7 is a left side view thereof.
